UNITED STATES PATENT OFFICE.

FRANK H. BANCROFT, OF GARDNER, MASSACHUSETTS, ASSIGNOR TO P. DERBY & CO., INC., OF GARDNER, MASSACHUSETTS, A CORPORATION OF MASSACHUSETTS.

ART OF UPHOLSTERY.

Application filed May 4, 1922. Serial No. 558,395.

To all whom it may concern:

Be it known that I, FRANK H. BANCROFT, a citizen of the United States of America, and resident of Gardner, in the county of 5 Worcester and State of Massachusetts, have invented new and useful Improvements in the Art of Upholstery, of which the following is a specification.

This invention relates to the art of upholstery and includes a method and apparatus for carrying the method into effect. The particular branch of the art to which the invention is especially applicable includes the making of box seats and similar devices in 10 which a cover usually of cloth, felt, leather or leather substitute is to be tightly and smoothly applied and made fast to a frame, such as a seat bottom. Padding or stuffing in sheet or loose form is ordinarily inserted 15 between this cover and the form, and this padding must be uniformly compressed and the cover tightly stretched thereover. With the cover held in a tightly stretched condition the marginal portions thereof are nailed 20 or otherwise made fast to the under side of the bottom.

The ordinary hand method of upholstering seats of this kind is laborious in the extreme as well as time consuming, since the 25 cover must be stretched and the padding compressed manually and manually held in place while the cover is made fast to the seat frame. In other words the upholsterer must be continually laying his hammer aside in 30 order to carry out the compressing and stretching phase of the operation and must hold the parts in compressed and stretched condition while he nails the cover to the seat frame.

40 Objects of the invention are to increase the speed and reduce the labor of upholstering box seats and the like, to attain the above object by mechanically stretching the cover and compressing the padding, to maintain 45 mechanically the cover and padding in stretched and compressed condition, respectively, while the cover is made fast to the chair bottom, to facilitate the fastening of the cover to the bottom by providing for the 50 rotation of the parts while in stretched and compressed condition, and in general to expedite the manufacture of box seats and the like and to improve the method of manufacture thereof.

The invention comprises the method of upholstering chair seats characterized by attaching the seat cover to a die, forcing the seat into the die (or the die over the seat) to stretch the cover, and then fastening the cover to the seat while the former is stretched. 55 If padding is inserted between the cover and the seat, the method further includes compressing the padding while the cover is being stretched. The invention further comprises apparatus for carrying the above method into effect, one concrete embodiment of such apparatus being shown in the accompanying drawings, by way of illustration, in which—

Fig. 1 is a side elevation; 70
Fig. 2 is a vertical section;

Fig. 3 is a horizontal section on the line 3—3 of Fig. 1;

Fig. 4 is an enlarged sectional view of the table with the clamping members in retracted position; 75

Fig. 5 is a section on the line 5—5 of Fig. 4;

Fig. 6 is a section on the line 6—6 of Fig. 4;

Fig. 7 is a section on the line 7—7 of Fig. 5;

Fig. 8 is a perspective view of one of the clamping members;

Fig. 9 is a plan view of the die; 85
Fig. 10 is a plan view of a completed chair seat taken from below;

Fig. 11 is a side elevation of the completed chair seat; and

Fig. 12 is a rear elevation thereof. 90

For the purpose of illustrating my invention I have shown in the accompanying drawings an embodiment thereof in which the steps of compressing the padding and stretching the cover over the seat frame or bottom is automatically performed and in 95 which the operator merely supplies the material to the apparatus, controls its operation, and nails the marginal portion of the cover to the bottom of the chair seat. The apparatus is mounted upon a frame comprising an upright I-beam 13 suitably supported upon a base 14 to which it is connected and braced by angle brackets 15. Fast upon the upright in spaced relation are castings 17, 18, 19 and 20. These castings are in 100 face engagement with one web of the I-beam and are fastened thereto by means of elongate bolts 21 extending through both webs.

thereof and retained in place by nuts 22. The two lower castings 17 and 18 support for rotation a table 23 having upon its upper face a block or plate 24 which serves as a key, for maintaining a suitable die 25 in proper and fixed position upon the top of the table, the block fitting in a slot 26 in the die (Fig. 9).

The die, in the present instance quadrilateral in form and shown in plan in Fig. 9, comprises a base portion 27 in which slot 26 is provided and peripheral members 28 upon the base. These peripheral members form a rim, the upper surface of which is provided with strips 29 of flexible material, preferably rubber. These strips are set in grooves in the top of the rim as indicated in Figs. 4 and 5 and extend slightly above the upper face of the peripheral members as shown. These peripheral members are inwardly and downwardly beveled, forming inclined surfaces 30. These surfaces are likewise grooved and provided with strips 31 of resilient material set therein. In use the seat cover is adapted to be placed across the die, being held at the corners by suitable fastening members such as pins 32 preparatory to stretching the cover over the seat frame. The marginal portions of the cover are tightly clamped upon strips 29. To prevent slipping of the cover, the upper surface of these strips is preferably roughened as indicated in Fig. 9.

To clamp the cover upon the rim of the die a plurality of clamping members 33 are provided about the periphery of table 23. These members are in the form of castings, one of which is shown in perspective in Fig. 8 and comprises parallelly disposed members 34 generally U-shaped in form connected at one end by an integral bridge piece 35, the opposite ends having aligned pivot openings 36 and cam projections 37. Upon the top of bridge piece 35 a plate 38 is fastened as by bolts or screws (not shown) extending through openings 39 (Fig. 8). Plates 38 extend beyond the bridge piece 35 and have attached to the under side thereof clamping bars 40 of any suitable material, preferably wood. These clamping bars are of a size substantially corresponding in length and width to strips 29 on the rim of the die. Clamping members 33 are hinged by pivots extending through openings 36 to links 41, in turn pivoted to the free ends of angular brackets 42 adjustably attached to the underside of table 23. These brackets are held in place by the combined gage and fastening members 43 shown in side elevation in Figs. 4 and 5 and in section in Fig. 7. As indicated in Fig. 7 the underside of the table 23 is provided with a series of integral projections 44 corresponding in number to the number of clamping members used, in this

case one to each side. These projections 44 are provided with elongate horizontally directed T-shaped slots 45, in the upper portion of which slots the central squared portion 46 of member 43 is adapted to slide. The right angular threaded bolt 47 extends through the lower portion of the slot, and clamps bracket 42 to the projection 44 by means of a nut 48. Member 43 has an upwardly and inwardly disposed engaging end 49, the parts being so proportioned that when the engaging end contacts the adjacent portion of the die, bracket 42 is disposed to so position clamping member 33 that clamping bar 40 will cooperate with strip 29 when the clamping member is in operative position.

Brackets 42 have a recess or opening 50 across which a pin 51 extends, serving as the anchorage for a coil spring 52 fastened at its opposite end to a pin 53 which connects the two links 41 provided for each of the clamping members 33. By the provision of this spring, links 41 are normally held in an upwardly inclined position as indicated in Fig. 4, disposing clamping members 33 outwardly inclined from the table 23 to provide easy access to the die in arranging the materials thereon in upholstering seats.

Means are provided for simultaneously swinging all of the clamping members 33 inwardly above the rim of the die and then directly downward to securely clamp the marginal edges of the cover. The means for accomplishing this preferably comprises a reciprocating rod 54 axially disposed within the hollow shaft 55 upon which table 23 is supported. The rod 54 is provided with two pins 56 and 57 vertically spaced and transversely disposed relative to the path of movement of the rod and angularly disposed relative to each other. These pins extend through elongate slots in hollow shaft 55 and receive therebetween crossed plates 58 and 59 (Fig. 6). Upper plates 58 are straight. Plates 59, two in number, are centrally depressed as indicated in Fig. 2 to receive plates 58 so that the ends of all plates are disposed in the same plane. Plates 58 are slotted at the ends to receive therebetween brackets 42. The free ends of all the plates extend over and beyond links 41 for operative contact with the cams 37 on clamping members 33. When rod 54 is depressed pin 57 operates to draw plates 58 and 59 downwardly so that clamping members 33 move from the position shown in Fig. 4, first to a position shown in dotted line in Fig. 5 and then to the position shown in full lines in Fig. 5. In the first movement of clamping members 33, the latter swing on the pivots extending through openings 36 and in the second or directly downwardly movement they pivot

on the connection of links 41 with brackets 42.

The support for table 23 comprises the hollow shaft 55 and the fluid pressure cylinder 60. The cylinder 60 has a lower casting 61, the lower end of which rests upon ball bearings 62 and is rotatably mounted in bearing 63 in casting 17. Hollow shaft 55 which is fast upon both cylinder 60 and table 23 is mounted for rotation in bearing 64 in casting 18 so that the entire assembly of table, clamping mechanism and means for operating the clamping mechanism rotates as a unit. Rod 54 as shown in Fig. 2 is fast to a piston 65 within cylinder 60, a spring 66 being provided to normally retain the piston in the upper part of the cylinder and to assist springs 52 in normally retaining the clamping members 33 in their retracted or inoperative position shown in Fig. 4.

The fluid pressure connection to the cylinder 60 comprises a pipe 67 (Fig. 1) extending from any suitable pressure source (not shown) and looped over the table in convenient position for the operator to manipulate a control valve 68 therefor and then downwardly through pipe 69 to a position directly beneath the cylinder, whence it leads upwardly by a pipe 70 to connect with an axial recess 71 in casting 61 of the cylinder, thence laterally out through a pipe 72 which leads upwardly into the top of the cylinder head at 73.

Disposed above the table in axial line with the shafts supporting the former is the mechanism for applying pressure downwardly upon the seat to stretch the cover and compress the padding. This mechanism comprises a fluid pressure cylinder 74 in all respects similar to cylinder 60 and supported by castings 19 and 20. To the piston 75 of the cylinder is attached a plunger 76 normally held in upwardly retracted position by a spring 77 which bears against the piston on the one hand and the cylinder casting on the other hand. The lower end of the plunger 76 is provided with a ball bearing device 78, the purpose of which will be later described. Fluid under pressure is conducted to cylinder 74 by means of a duct or pipe 79 provided with a control valve 80 in position to be readily manipulated by the operator.

A follower 81 is mounted for swinging movement beneath plunger 76. This follower has a sliding pivotal connection with an arm 82 by means of a bolt and nut connection 83 (Fig. 5), the nut fitting in a counter-bored slot 84 in the arm. Arm 82 is clamped to rod 85 by a sleeve 86, the rod being supported for rotation by brackets 87 fast on I-beam 13. As shown in Fig. 1 sleeve 86 is normally disposed in spaced relation to upper bracket 87 by the provision of a coil spring 88 surrounding rod 85.

The operation of the device is as follows: The operator places upon table 23 a die 25 of the type described, of the proper size to form the desired size and shape of the box or slip seat, with block 24 on the table fitting in slot 26 in the die. A seat cover 90, Figs. 3 and 5, is then spread smoothly across the die with pins 32 holding it securely in place at each corner. Valve 68 is then opened to admit fluid under pressure into the upper end of cylinder 60, whereby piston 65 is forced downwardly against spring 66, the pin 56 on rod 54 attached to the piston drawing plates 58 and 59 downwardly to move clamping brackets 33 first inwardly and then downwardly as previously described. The marginal edges of the cover are accordingly tightly clamped by clamping bars 40 upon the resilient strips 29 which have a roughened surface and hence securely hold the cover against slipping. Upon the top of cover 90 padding 91, Fig. 5, is placed, this padding being either in sheet form or loose and evenly applied over the central portion of the cover as desired. Upon the padding is placed the seat frame or bottom 92, Figs. 3 and 5. The operator now swings follower 81 above the table, spring 88 holding it sufficiently elevated to clear the seat bottom. The follower 81 is properly centered with the bolt and nut connection 83 is directly beneath the roller bearing 78 upon plunger 76. Valve 80 is then opened to admit fluid under pressure to cylinder 74 to depress piston 75 which through plunger 76 and bearing 78 acts upon follower 81 to force the seat frame 92 downwardly into the die, thus stretching the cover 90 and compressing the padding 91. Fig. 5 shows the seat frame driven home under the pressure applied to follower 81, spring 88 permitting the downward movement of the follower.

The operator now turns valve 68 to release the pressure in piston 60 whereupon clamping members 33 under the impulse of springs 52 acting on links 41 and of spring 66 acting upon piston 65 are forced first upwardly and then outwardly releasing the marginal portions of the cover. The operator now folds these marginal portions of the cover over upon the adjacent portions of the seat frame and nails them in place, rotating table 23 as desired to bring the work into convenient position, ball bearing 78 preventing plunger 76 from interfering with the rotative movement. When the cover has been nailed entirely around its periphery to the chair bottom pressure is relieved in the upper cylinder 74 by operating valve 80, whereupon the plunger 76 retracts and the follower 81 rises under the impulse of spring 88. The follower is then moved to one side whereupon the completed chair seat may be removed. The completed chair seat

is shown in bottom plan view in Fig. 10, portions of cover 90 being slotted adjacent the corners as indicated at 95 to form a smooth attachment and avoid folds and creases. The complete chair seat is further shown in side elevation and in rear elevation in Figs. 11 and 12 respectively.

The changing of the die when chair seats of a different size are to be made is a simple matter by reason of the provision of the combined gage and fastening mechanism 43. By releasing nuts 48 the members 43 may be moved outwardly slightly together with brackets 42 to release the die then on the table whereupon the same may be removed and the new one adjusted in place with centering block 24 in slot 26. Members 43 will now be forced inwardly toward the die until the gage end 49 contacts the die whereupon the nuts 48 are again tightened to securely fix the clamp supporting brackets 42 in place. These brackets are now properly positioned, so that when clamping members 33 are forced downwardly upon the die the 25 clamping bars 40 will register with the strips 29.

In the form shown relatively large fluid pressure rams are used, those shown being six and eight inches in diameter respectively, and a pressure of approximately ninety pounds to the square inch is employed. These dimensions and this pressure are found adequate to hold the marginal portions of the cover in place, to insure proper stretching of the cover, and to properly and smoothly compress the padding between the seat and the cover so that an upholstered seat is produced equal, if not superior, in all respects to the best work done by hand. The saving in time over the hand method is at least 50% and may become greater as the operator becomes highly skilled in the use of the machine. In addition the labor of operating the machine is 45 relatively slight and is much less wearing and exhausting upon the operator than the hand method.

I claim:

1. Apparatus for upholstering chair seats and the like comprising a die, rotatable means for supporting the die, means for holding a cover on said die, and means for forcing a seat bottom into said die to stretch the cover and maintain the cover stretched 55 while it is being fastened to the seat bottom, said last named means acting on said seat bottom through a follower supported independently of said last named means.
2. Apparatus for upholstering chair seats and the like comprising a support adapted to receive thereon removable and interchangeable dies, means on said support for maintaining a die against movement relative to said support, and means on said sup-

port adjustable to the size of a die for holding a cover upon said die.

3. Apparatus for upholstering chair seats and the like, comprising a support, a die fitting upon said support, and means for clamping a cover upon said die including clamping bars mounted upon said support and arranged to be operated in unison to clamp or to release the cover.

4. Apparatus for upholstering chair seats comprising a support, a die thereon, means maintaining said die in fixed position upon said support, clamping bars pivoted to said support, and means for simultaneously actuating said bars to clamp a cover upon the 80 upper face of said die.

5. Apparatus for upholstering chair seats comprising a support, a die thereon, clamping bars pivoted to said support and normally disposed outwardly therefrom, and means for swinging said bars inwardly and then down to clamp the marginal portions of a cover upon the upper face of said die, said bars being arranged to operate in unison.

6. Apparatus for upholstering chair seats comprising a support, an interchangeable die thereon, means maintaining said die in fixed position upon said support, clamping bars adjustably mounted upon said support, and means for actuating said bars to clamp a cover upon said die.

7. Apparatus for upholstering chair seats comprising a support, a die thereon, a clamping bar adjustably mounted upon said support for swinging movement, and means operable to swing said bar over said die and then down to clamp a cover thereon.

8. Apparatus for upholstering chair seats comprising a support, a die thereon, means maintaining said die in fixed position upon said support, a bracket adjustably mounted on said support, a clamping bar mounted on said bracket, and means for actuating said bar to clamp a cover upon said die.

9. Apparatus for upholstering chair seats comprising a support, a die thereon, a bracket adjustably attached to said support by a combined gage and adjustment member, a member having a clamping bar pivoted on said bracket, and means for actuating said last named member to clamp a cover upon said die.

10. Apparatus for upholstering chair seats comprising a support, a die thereon, means maintaining said die in fixed position upon said support, a bracket adjustably mounted on said support, an arm pivoted to said bracket, a member having a clamping bar pivoted to said arm, and means for actuating said member to clamp a cover upon said die.

11. Apparatus for upholstering chair seats comprising a support, a die thereon, a bracket mounted on said support, arms 130

- 11 pivoted to said bracket, a member pivoted to said arms and bent around said support and provided at its free end with a clamping bar, and means for actuating said member to cause said bar to clamp a cover upon said die.
12. Apparatus for upholstering chair seats comprising a support, a die thereon, means maintaining said die in fixed position upon said support, a bracket mounted on said support, arms pivoted to said bracket, a member pivoted to said arms and bent around said support, and provided at its free end with a clamping bar, said member having an inwardly disposed cam projection, and means actuating said member through its cam projection and pivotal connections to clamp a cover upon said die.
13. Apparatus for upholstering chair seats and the like, comprising a support, a die thereon, a clamping member having a double pivotal connection with said support, and means for actuating said member to clamp a cover upon said die.
14. Apparatus for upholstering chair seats and the like, comprising a support, a die thereon, a clamping member normally disposed outwardly and at an angle to said support, and means operable to move said member inwardly and then downwardly to clamp a cover upon said die.
15. Apparatus for upholstering chair seats and the like comprising a support, a die thereon, a clamping member having a double pivotal connection with said support, said connection being such that movement upon one pivot swings said member over said die and movement on the other pivot draws said member downwardly to clamp a cover upon said die.
16. Apparatus for upholstering chair seats comprising a support, a die thereon, a plurality of clamping bars movably mounted upon said support and means for simultaneously actuating said bars to clamp a cover upon said die.
17. Apparatus for upholstering chair seats comprising a support, a die thereon, a plurality of clamping bars movably mounted upon said support and means for simultaneously actuating said bars to clamp a cover upon said die, said support, bars and actuating means being rotatable as a unit.
18. Apparatus for upholstering chair seats comprising a rotatable table, a hollow shaft supporting said table, a plurality of clamping members mounted on said table, and means including a reciprocable member within said shaft for actuating said clamping members.
19. Apparatus for upholstering chair seats comprising a rotatable table, a hollow shaft supporting said table, a plurality of clamping members pivotally mounted on said table, and means including a recipro-
20. Apparatus for upholstering chair seats comprising a support, a shaft on which said support is rotatably mounted, a plurality of clamping members mounted on said support, and fluid pressure actuated means mounted on said shaft for operating said clamping members.
21. Apparatus for upholstering chair seats comprising a rotatable table, a shaft supporting said table and rotatable therewith, a plurality of clamping members mounted on said support and fluid pressure actuated means mounted on said shaft for operating said clamping members.
22. Apparatus for upholstering chair seats comprising a table, a hollow-shaft supporting said table, a plurality of clamping members pivoted to said table, and means for actuating said members including a reciprocable rod within said shaft and members extending from said rod to each of said clamping members.
23. Apparatus for upholstering chair seats comprising a table, generally quadrilateral in form, a clamping member pivoted to said table adjacent each side thereof, a hollow shaft rotatably supporting said table, and means for simultaneously actuating said members including a reciprocable rod within said shaft and crossed members connected to said rod and extending to each of said clamping members.
24. Apparatus for upholstering chair seats comprising a table, a plurality of clamping members, each pivoted to links in turn pivoted to said table, cam projections on the inner ends of said members, crossed plates having their ends disposed adjacent to and above said cam projection, and means for reciprocating said plates, said parts being constructed and arranged to first swing said clamping members inwardly over said table and then downwardly to clamping position.
25. Apparatus for upholstering chair seats comprising a table, a hollow shaft supporting said table, a plurality of clamping members, each pivoted to links in turn pivoted to said table, cam projections on the inner ends of said members, crossed plates having their ends disposed adjacent to and above said cam projection, a rod reciprocable within said hollow shaft and connected to said crossed plates, and fluid-pressure means mounted on said shaft for reciprocating said rod, said plates and said clamping members being so constructed and arranged that downward movement of said rod moves said clamping members simultaneously first inwardly and then downwardly.
26. Apparatus for upholstering chair seats comprising a support, a die main-

- 2 tained in fixed position upon said support, a plurality of clamping members mounted on said support for clamping a cover upon said die, means for conjointly actuating said members, and means for forcing a seat bottom into said die to stretch said cover.
27. Apparatus for upholstering chair seats, comprising a support, a die maintained in fixed position upon said support, 10 a plurality of clamping members mounted on said support for clamping a cover upon said die, means for conjointly actuating said members, a follower mounted adjacent said support for movement thereover and adapted to be positioned above a seat bottom placed on the cover, and means acting on said follower for forcing the seat bottom into said die to stretch said cover.
28. Apparatus for upholstering chair 20 seats, comprising a support, a die maintained in fixed position upon said support, a plurality of clamping members mounted on said support for clamping a cover upon said die, a follower mounted adjacent said support for free swinging movement thereof and adapted to be positioned above a seat bottom placed on the cover, and a plunger acting on said follower for forcing the seat bottom into said die to stretch said cover.
29. Apparatus for upholstering chair 30 seats comprising a support, a die thereon, means for clamping a cover across said die, a follower mounted for swinging movement over said support to be positioned above a seat bottom placed upon said cover, and a plunger adapted to contact said follower and force it downwardly thereby to cause said cover to be stretched over said seat bottom, and means for reciprocating said plunger.
30. Apparatus for upholstering chair seats comprising a support, a die thereon, means for clamping a cover across said die, a follower rotatably mounted upon a swinging 45 arm for movement over said support to be positioned above a seat bottom placed upon said cover, and a plunger adapted to contact said follower and force it downwardly thereby to cause said cover to be stretched over said seat bottom, and fluid pressure means for operating said plunger in one direction.
31. Apparatus for upholstering chair 50 seats comprising a rotatable support, a die thereon, a plunger for forcing a seat bottom into said die, and a ball bearing upon the end of said plunger for permitting rotation of said support while the plunger is in operative position.
32. Apparatus for upholstering chair 55 seats comprising a support, a die thereon, means for clamping a cover upon said die, a plunger for forcing a seat bottom into said die to stretch the cover thereover, and a follower movable into and out of opera-
- tive association with said plunger to receive the thrust of the latter and transmit it to the seat bottom.
33. Apparatus for upholstering chair 60 seats comprising a support, a die thereon, means for clamping a cover upon said die, and means for forcing a seat bottom into said die to stretch the cover thereover including a follower mounted upon a swinging arm for movement over said support 75 to a position above said die and seat bottom.
34. Apparatus for upholstering chair 70 seats comprising a support, a die thereon, means for clamping a cover upon said die, a follower mounted upon a swinging arm 80 for movement to a position above said cover and a seat bottom thereon, means for normally maintaining said follower above said cover and seat but permitting downward movement thereof, and means adapted to 85 contact said follower to thereby force said seat bottom into said die to stretch the cover thereover.
35. Apparatus for upholstering box seats 90 comprising a support, a die thereon, and means for clamping a cover upon said die, said die having a marginal rim providing a substantially plane surface upon which the marginal portions of a seat cover may be clamped, means providing a yielding 95 surface for said rim, means for retaining a cover upon said die, and inwardly beveled surfaces adapted to shape said cover about a seat bottom forced into said die to stretch said cover thereover.
36. Apparatus for upholstering box seats 100 comprising a support, a die thereon, and means for clamping a cover upon said die, said die being constructed and arranged for shaping and stretching the cover over a seat bottom and comprising surfaces for contacting portions of the cover previous to being stretched and other surfaces for contacting the cover after being stretched, and resilient material forming said surfaces 105 to prevent injury to the cover.
37. Apparatus for upholstering box seats 110 comprising a support, a die thereon, and means for clamping a cover upon said die, said die being constructed and arranged for shaping and stretching the cover over a seat bottom comprising surfaces for contacting portions of the cover previous to being stretched and other surfaces for contacting the cover after being stretched, said surfaces being formed by strips of resilient material attached to said die to prevent injury to the cover, certain of said strips having 115 roughened surfaces.
38. Apparatus for upholstering box seats 120 comprising a support, a die thereon, and means for clamping a cover upon said die, said die being constructed and arranged for shaping and stretching the cover over a seat bottom and comprising a rim upon 125

which the marginal portions of a seat cover are to be clamped, inwardly beveled surfaces extending downwardly from said rim, and strips of resilient material on said rim and said surfaces to prevent injury to said cover.

39. Apparatus for upholstering box seats comprising a support, a die thereon, and means for clamping a cover upon said die, 10 said die being constructed and arranged for shaping and stretching the cover over a seat bottom comprising a rim upon which the marginal portions of the cover are to be clamped, strips of resilient material having 15 a roughened surface being provided on said rim to hold the cover against slipping, said die having beveled surfaces extending inwardly and downwardly from said rim, and strips of resilient material fitting in grooves 20 and flush with said surfaces to prevent injury to said cover when stretched and forced into contact therewith.

40. In a device of the class described, a

support, a die thereon, means for clamping a cover upon said die including a plurality 25 of clamping bars arranged for simultaneous operation and a control member for said means whereby movement of said member in one direction causes said means to become operative and movement thereof in a 30 different direction causes said means to become inoperative.

41. In a device of the class described, a support, a die thereon, a plurality of members pivoted to said support for clamping 35 a cover upon said die, said members being normally disposed away from said die, means for simultaneously actuating said members, and a manual control for said means constructed and arranged to produce 40 simultaneous movement of said members to clamping position or reverse movement to normal position.

Signed by me at Gardner, Massachusetts, this 24th day of April, 1922.

FRANK H. BANCROFT.
